UNITED STATES PATENT OFFICE.

JOHN REICHEL, OF CAMDEN, OHIO.

ATTACHMENT FOR GRAIN BINDERS.

Application filed November 21, 1922. Serial No. 602,464.

To all whom it may concern:

Be it known that I, JOHN REICHEL, a citizen of the United States, and resident of Camden, in the county of Preble and 5 State of Ohio, have invented a new and useful Attachment for Grain Binders, of which the following is a full, clear, and exact description, reference being had to the accompanying drawings, forming a part 10 of this specification.

My invention relates to attachments for grain binders.

In the operation of grain binders difficulty frequently arises by reason of grain and straw passing between the platform and lower elevator conveyor webs. Some of this grain and straw passes thru and drops on to the ground and the grain is thus lost, some of the balance is carried around by 15 the platform conveyor web and becomes wedged between the platform and the web where it causes excessive wear upon the web resulting in damage thereto, or may clog the mechanism to such an extent as to prevent 20 efficient operation thereof.

The principal object of this invention is to provide an attachment for a grain binder whereby the difficulties mentioned may be effectually overcome.

30 Further objects of the invention will appear from the following detailed description thereof.

In the drawings:—

Figure 1 is a perspective of my new attachment;

Figure 2 is an end elevation of the conveyor mechanism with my attachment in place;

Figures 3 and 4 are end elevations of two forms of the attachment.

40 The numeral 1 indicates the platform of a grain binder, and 2 the platform conveyor web, which operates upon rollers 3 and 4. The web is provided with cross-members 5. The upper and lower elevator webs are in-

45 dicated by numerals 6 and 7 respectively, said webs operating over rollers 8—8 and 9—9 respectively. Said webs are also provided with cross-members 5. The several elements heretofore described may be of any

50 of the usual types well known in grain binders now in general use, and for the purpose of explaining this invention I have illustrated the same in the drawings somewhat diagrammatically, related parts of the binder mechanism being omitted for the sake of clearness and simplicity in illustrating the

present invention. In use the several webs operate in the directions of the arrows in Figure 2, and grain is carried over the platform conveyor 2 to the elevator conveyors where it is gripped between the two webs and carried upwardly to the binding mechanism.

My new attachment consists of a sheet metal plate or guard 10 shaped in section as 60 clearly shown in the several figures of the drawings. Said guard plate is of a length substantially corresponding to the width of the platform 1.

My guard plate 10 is provided with reinforcing members or bars 11, of which there may be any suitable number, three being shown in the drawings, said bars are secured by screws or rivets to the plate 10. The lower ends of the bars 11 are provided with 65 angular flanges 12 which form slots 13 in conjunction with the lower edge of the guard plate 10, arranged to receive the inner edge 14 of the platform 1. The guard plate may thus be attached merely by placing the 70 same so that the edge 14 of the platform rests in the slots 13, as shown in Figure 2 of the drawings.

In Figure 4 I have shown a modification 75 wherein the flange 12 does not serve to form a slot but is adapted to receive a bolt 15 by means of which it is attached to the platform, this method being preferable in certain types of binding machine construction. The guard may also be permanently in- 80 stalled on the machine when made.

From the foregoing description the nature 85 of the present invention will be apparent to those skilled in the art to which it appertains. Where grain is carried by the conveyor web 2 in the direction of the arrow, there is a tendency when it reaches the end of said web for it to pass between it and the lower end of the elevator web 7. It is thus permitted, if released by the web 2 before being carried under, to drop on to the ground and is wasted. Where, however, it is carried under by web 2 it clogs between the web and the platform and thus causes damage to the web or reduces the efficiency of 90 operation thereof. When my new attachment is in place on the machine it will be seen that grain and straw is not permitted to fall on to the ground, being intercepted by the guard plate 10. Furthermore, when straw passes between the two webs, and would tend otherwise to lodge between the 95 100 105 110

platform and platform web, it is prevented by the lower edge of the guard plate from passing under the web 2, said edge being in close proximity to the strips 2 during their 5 passage.

It is thus obvious that by the use of my new attachment the binder mechanism is protected and the wastage of grain overcome.

10 It will also be apparent that my new attachment may readily be placed into position for use and may as readily be removed when desired.

Having thus fully described my invention, what I claim as new and desire to 15 secure by Letters Patent is:—

In combination with the platform and conveyor mechanism of a grain binder, an attachment comprising a guard plate, reinforcing bars secured to said plate, the lower 20 ends of said bars being provided with flanges arranged to cooperate with the lower edge of said plate whereby said plate may be secured to the platform underneath said conveyor mechanism.

JOHN REICHEL.
